UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND-BRAKE.

1,344,309.

Specification of Letters Patent. Patented June 22, 1920.

Application filed October 16, 1918. Serial No. 258,454.

To all whom it may concern:

Be it known that I, JOHN F. O'CONNOR, a citizen of the United States, residing at Chicago, in the county of Cook and State 5 of Illinois, have invented a certain new and useful Improvement in Hand-Brakes, of which the following is a full, clear, concise, and exact description, reference being had to the accompanying drawings, forming a 10 part of this specification.

This invention relates to improvements in hand brakes.

As is well known to those skilled in the art, there has been a pressing demand for 15 some time for a hand brake for railway cars which would have greater leverage ratio than the type of hand brake which has been in most common use, that is, the hand brake of the vertical staff type employing 20 an ordinary hand wheel at the top thereof. Numerous attempts have been made to satisfy this demand, the most common method being to employ a hand lever for actuating a pawl and ratchet mechanism to rotate the 25 staff step-by-step. Some attempts have also been made to employ a multiplying gearing and in certain instances the two expedients just mentioned have been combined.

While many of the forms of brakes above 30 indicated accomplish the result sought of increasing the leverage ratio, they have not met with complete success because of the unfamiliarity of the brakemen with their method of operation. The brakemen have 35 always been accustomed to turning a hand wheel while standing in a certain position and the new types of hand brakes have necessitated a different method and position of the brakemen while being operated. Also, 40 in many instances while the increased leverage ratio has been obtained, the same has only been accomplished by sacrificing considerable of the speed of operation during the preliminary winding movement when 45 the slack of the chain is taken up.

One object of my invention is to provide a simple, efficient hand brake of the vertical staff type for railway cars wherein the brake is operated in the well known manner by a 50 hand wheel and so arranged that the slack of the chain is taken up as rapidly as with the old type of brakes and the final tightening movement accomplished automatically with a much increased leverage ratio. 55 Another object of the invention is to pro-

vide a hand brake of the vertical staff type having means for rapidly winding the brake chain while slack and adapted automatically to increase the leverage ratio as the chain tightens without any change in manner of operating the brake on the part of the brakeman. 60

Another object of the invention is to provide a hand brake of the character above indicated and so designed that the usual 65 foot-operated locking pawl and ratchet can be entirely omitted without detriment.

Other objects of the invention will more fully appear from the description herein-after following. 70

In the drawing forming a part of this specification, Figure 1 is a part side elevational view, part vertical section of a hand brake showing my improvements embodied therein. The figure illustrates the lower 75 portion of the end of a freight car showing my improved brake applied in the most common position and leaving the vertical brake staff in its usual location. Figs. 2 and 3 are horizontal, sectional views, taken on the 80 lines 2—2 and 3—3, respectively, of Fig. 1. Fig. 4 is a vertical, sectional view taken on the line 4—4 of Fig. 1.

In said drawing, 10 denotes the end sill of a railway car, 11 one of the end posts and 85 12 the outer sheathing. The improved brake, as shown, comprises broadly a securing bracket A, a sliding bracket or cross-head B, a vertical staff C, hand wheel D, worm E, worm nut F and brake chain G. 90

As shown, the bracket A comprises a vertical wall 13, a horizontal flange 14 and downwardly and outwardly extended arm 15 having a journal bearing 16 at its outer end. As clear from the drawing, the arm 95 15 is suitably strengthened by flanges 17—17 and vertical webs 18—18. The vertical section 13 of the bracket A is formed with guideways 19—19 on each side thereof with which coöperate tongues 20—20 formed on 100 the sliding bracket or cross-head B. The cross-head B is shown in Fig. 1 as in its lowermost position, and as will be apparent, the same is adapted to slide upwardly on the bracket A. Said bracket A is secured to the 105 car in any suitable manner as by the bolts and lag screws 21—21.

The cross-head B is formed at its upper end with a horizontally and outwardly extending arm 22 having a journal bearing 110

section 23 in alinement with the journal bearing section 16 of the bracket A. Said horizontal arm 22 of the cross-head B is suitably braced by upwardly and downwardly extending vertical flanges 24-24, as clearly shown in Figs. 1 and 4. Near the bottom thereof, the cross-head B has a chain idler pulley 25 rotatably mounted on a journal 26 mounted in suitable bosses 27 formed integrally on the cross-head B. As clearly appears from Figs. 2, 3 and 4, the idler pulley 25 is disposed to one side of the cross-head B and opposite an opening 28 provided in the vertical portion of the cross-head B, for the purpose hereinafter described. A corresponding chain idler pulley 29 is rotatably mounted in the bracket A in alinement with the pulley 25. The chain G passes under the pulley 29 and then over the pulley 25 and has its end link 30 attached to the combined worm nut and drum or spool F.

The staff C, at its lower end, is squared, as indicated at 31, and has the worm E applied thereon so that the worm rotates in unison with the staff. The worm E is limited in its upward movement on the shaft C by a suitable collar 32 and at its lower end is provided with a journal section 33 rotatable within the journal bearing 16 of the bracket A. A collar is provided on the worm E near its lower end as indicated at 34, to limit the downward movement of the worm.

A worm nut F is interiorly threaded to coöperate with the steep pitch threads of the worm E. The worm nut F at its upper end is provided with an annular extension bushing or sleeve 35 which fits within the journal bearing section 23 of the cross-head B. Said nut F has a cylindrical outer surface and it is formed with upper and lower annular flanges 36 and 37 so that the nut F acts as a winding drum or spool for the chain G. In actual practice, I preferably employ four threads on the worm E and make them of relatively steep pitch for the purpose hereinafter explained. By offsetting the pulleys 25 and 29, as heretofore explained, it will be seen that I am enabled to bring the brake chain G from the pulley 25 tangentially to the drum F while leaving the latter and the brake staff located centrally with respect to the cross-head B.

The operation is as follows: Assuming the parts in the position shown in Fig. 1, that is, with the brake not set and the chain with the usual amount of slack therein, the drum F will have its upper collar 36 free from engagement with the cross-head B. If now the brakeman turns the hand wheel D in the usual manner, that is, to rotate the staff C in a clockwise direction, as viewed in Figs. 2 and 3, the chain will start to wind around the drum F. With the chain slack, the friction between the worm and drum F

will be greater than the force required to take up the slack in the chain. In other words, during the preliminary action, the drum will rotate in unison with the staff so as to quickly take up the slack. As the 70 brake chain begins to tighten and the tension thereon is increased to a certain amount, the resistance to the rotating movement of the drum will overcome the friction between the drum nut and the worm E. Consequently, as the drum nut F ceases to rotate and the rotation of the staff C is continued, the drum nut will automatically climb up the worm E and in so doing the flange 36 will be brought into tight frictional contact 80 with the cross-head B and the latter in turn will move upwardly in unison with the drum nut F. The drum nut F being held against rotation and traveling vertically upwardly and in unison with the cross-head B, will 85 pull the chain G over the idler pulley 29 and consequently the tension on the brake chain will be increased in accordance with the amount of vertical movement of the cross-head B. Furthermore, because of the 90 arrangement of worm and worm nut, there is no danger of the brake staff turning back accidentally nor is any locking pawl and ratchet mechanism required. The device is self-locking in any adjusted position which 95 gives the brakeman greater freedom in applying the brakes. In addition, the self-locking feature permits the brakeman to ease off the brake chain by degrees so that, in spotting the cars in a hump-back yard, he 100 can graduate the braking resistance as desired.

As will be evident to those skilled in the art, various changes and modifications may be made in the details of construction without departing from the spirit of the invention.

I claim:

1. In a hand brake for cars, the combination with a vertical brake staff and hand wheel for turning the same, of a chain winding drum, means for rotating said drum when the staff is rotated and while the chain is slack, and means adapting the drum to shift axially after the slack is taken up in 110 the chain to thereby continue the tightening of the chain.

2. In a hand brake for railway cars, the combination with a vertical brake staff and means for turning the same, of a chain 120 winding drum, and mechanism for either rotating or shifting said drum axially upon rotation of the staff, dependent upon the degree of brake chain tension on the drum.

3. In a hand brake for railway cars, the combination with a vertical brake staff and means for turning the same, of a chain winding drum, and mechanism for either rotating or shifting said drum axially upon rotation of the staff, dependent upon the 130

degree of brake chain tension on the drum, said mechanism including a worm and worm nut interposed between the staff and drum.

4. In a hand brake for railway cars, the combination with a vertical brake staff and means for turning the same, of a chain winding drum, and mechanism for either rotating or shifting said drum axially upon rotation of the staff, dependent upon the 10 degree of brake chain tension on the drum, said mechanism including a worm, a worm nut, and a non-rotatable element adapted for frictional contact with said drum to prevent rotation of the latter when the tension 15 has increased beyond a certain point.

5. In a brake of the character described, the combination with a manually operable rotatable element, of a brake chain, a drum on which to wind said chain, and mechanism 20 interposed between said drum and element adapted to rotate the drum upon rotation of said element while the chain is slack, said drum being shiftable axially thereof when the tension on the chain reaches a 25 determined point, the axial movement of the drum thereby increasing the tension on the chain.

6. In a device of the character described, the combination with a rotatable operating 30 element, of a chain winding drum, a chain attached at one end to said drum, leverage ratio multiplying means interposed between said element and drum adapted to rotate said drum when the chain tension is less 35 than a predetermined amount and thereafter shift the drum axially when the degree of chain tension on the drum exceeds said amount.

7. In a hand brake for railway cars, the 40 combination with a bracket adapted to be secured to the end of the car, of a vertical brake staff, a chain winding drum carried by said staff at the bottom thereof, a brake chain attached to the drum, a cross-head

vertically slidably mounted on said bracket 45 and over which the brake chain passes, and means coöperable with said staff and drum for elevating the latter when the staff is rotated, the drum coöperating with said cross-head to elevate the latter to thereby increase 50 the brake chain tension.

8. In a brake for railway cars, the combination with a bracket adapted to be secured to the car and a cross-head slidably mounted on said bracket, said bracket and 55 cross-head each having idler pulleys for the brake chain, of a brake chain passing over said idler pulleys, a vertical staff, a chain winding drum mounted thereon and to which said chain is attached, said drum being adapted for axial movement in addition to its rotative movement, and means operated by the staff for imparting either 60 rotative or axial movement to said drum at different times, dependent upon the brake 65 chain tension.

9. In a brake for railway cars, the combination with a bracket adapted to be secured to the car and a cross-head slidably mounted on said bracket, said bracket and 70 cross-head each having idler pulleys for the brake chain, of a brake chain passing over said idler pulleys, a vertical staff, a chain winding drum mounted thereon and to which said chain is attached, said drum being adapted for axial movement in addition to its rotative movement, and means operated by the staff for imparting either 75 rotative or axial movement to said drum at different times, dependent upon the brake 80 chain tension, said means including a worm on the brake staff and a worm nut rotatable in unison with the drum.

In witness that I claim the foregoing I have hereunto subscribed my name this 14th 85 day of Oct., 1918.

JOHN F. O'CONNOR.
